Primary Examiner — Lilyana Bekic(57) **CLAIM**

The ornamental design of a snorkel mask, as shown and described.

DESCRIPTION

FIG. 1 is a front perspective view of a snorkel mask showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is another rear perspective view thereof, shown with a strap attached.

The broken lines in the drawings depict portions of the snorkel mask that form no part of the claim.
